The ornamental design for a connector for an I.V. bag, as shown and described.

DESCRIPTION

FIG. 1 is a front elevational view of a connector for an I.V. bag showing my new design;

FIG. 2 is a side elevational view of a connector for an I.V. bag;

FIG. 3 is a side elevational view of the opposite side of a connector for an I.V. bag;

FIG. 4 is a top plan view of a connector for an I.V. bag;

FIG. 5 is a bottom plan view of a connector for an I.V. bag;

FIG. 6 is a rear elevational view of a connector for an I.V. bag;

FIG. 7 is a perspective top view of a connector for an I.V. bag; and,

FIG. 8 is a perspective bottom view of a connector for an I.V. bag.
